US00D588112S

(12) **United States Design Patent**
Komiyama

(10) **Patent No.:** **US D588,112 S**
(45) **Date of Patent:** **** Mar. 10, 2009**

(54) **HEADPHONE**

(75) Inventor: **Jun Komiyama**, Tokyo (JP)

(73) Assignee: **Sony Corporation**, Tokyo (JP)

(**) Term: **14 Years**

(21) Appl. No.: **29/300,380**

(22) Filed: **Mar. 20, 2008**

(30) **Foreign Application Priority Data**

Oct. 15, 2007 (JP) D2007-028145

(51) **LOC (9) Cl.** **14-01**

(52) **U.S. Cl.** **D14/223; D14/205**

(58) **Field of Classification Search** D14/205,

(57) **CLAIM**

The ornamental design for a headphone, as shown and described.

DESCRIPTION

FIG. 1 is a perspective front view of a headphone showing my new design;

FIG. 2 is a perspective rear view of a headphone showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The portions indicated in broken lines are for illustrative purposes only and form no part of the claimed design. The dot-dash broken lines shown in Drawings define but are not included in, the boundaries of the claimed design.

1 Claim, 8 Drawing Sheets
